UNITED STATES PATENT OFFICE.

JAMES JOHN WALKER, OF LONDON, ENGLAND.

AUTOMATIC MUSICAL INSTRUMENT.

1,179,688.

Specification of Letters Patent. Patented Apr. 18, 1916.

Application filed July 10, 1911. Serial No. 637,761.

To all whom it may concern:

Be it known that I, JAMES JOHN WALKER, a subject of the King of the United Kingdom of Great Britain and Ireland, and residing at 27 Francis street, Tottenham Court Road, London, England, have invented new Improvements in or Relating to Automatic Musical Instruments, of which the following is a specification.

10 This invention relates to automatic musical instruments the playing of which is controlled by a perforated tune sheet traveling over a tracker board having ports operatively connected with the respective note-sounding motors, and it has for its object 15 to provide improved means by which the said tune sheet can be automatically maintained in, or returned to, its proper position for insuring register between its respective rows of note slots or perforations and 20 the respective tracker board ports.

Hitherto the automatic control of the tune sheet in respect of its transverse or lateral adjustment on the tracker board has been 25 effected through ports controlled by:—(a) the edges of the tune sheets, or perforations near those edges, which arrangements have been found unreliable because the normal register of the said edges or perforations 30 with the respective so-called control ports is so readily disturbed by lateral expansion and contraction of the tune sheet due to climatic influence, and (b) perforations in the tune sheet adapted to coöperate with 35 control ports arranged in the line of the note-controlling ports of the tracker board and not to coöperate with the said note-controlling ports, which arrangement involves a proportionate increase in the width 40 of the tune sheet.

It is known that during the normal travel of a tune sheet, perforations in such sheet of less than a given area relatively to the area of the ordinary ports of a tracker 45 board, can register with those ports without, in any way, affecting the playing of the music, the reason being that the perforations are not large enough to allow air to pass therethrough in sufficient volume to admit 50 of the motors connected with the said ports becoming operative or responsive.

The present invention avails itself of that property of irresponsiveness of the coöperation of undersized tune sheet perforations 55 with the ordinary tracker board ports, and provides means whereby it can be advan-

tageously utilized in connection with the automatic control of the tracking position of the tune sheet relatively to the tracker board, and with that in view the said invention may be said to consist partly in the use, in combination with tune sheet perforations which are too small to render the usual tracker board ports responsive, of other ports which those perforations can 60 render responsive.

It further consists in means whereby the said perforations, while themselves arranged in interrupted rows or lines, exercise an uninterrupted control over the relative positions of the tune sheet and tracker board.

The invention will be best understood by reference to the accompanying drawings in which:—

Figure 1 is a plan showing part of a tune 75 sheet and tracker board, the former in correct tracking position relatively to the latter, and Fig. 2 is a similar view showing the tune sheet in incorrect position relatively to the tracker board.

According to the present invention the tracker board 1, besides being provided with the ordinary ports 2, a, b, c, and d is provided with ports 3, 4, hereinafter referred to as register control ports, situated at either 80 the front or rear of the ports 2 or, as shown in the drawings, each register control port 3, 4, may be formed in two portions one at the front and the other at the rear of the said ordinary ports. The two portions of 85 each register control port 3, 4 are alined with each other in the direction of travel of the tune sheet 5, and both of the register control ports 3 are pneumatically connected together and to a motor which, when actuated, serves, for example in well-known 90 manner, to move either the tune sheet 5 rightward or the tracker board 1 leftward. Correspondingly, both of the register control ports 4 are pneumatically connected to 95 together and to a motor which latter, when actuated, serves for example, to move either the tune sheet 5 leftward or the tracker board 1 rightward; or the said motors may effect the restoration of the tracking register between the tracker board 1 and the tune sheet 5, in any other convenient manner, for example, in the manner set forth in the specification of my former Letters Patent

No. 911,789 dated 9th February, 1909. The 100 last mentioned motors, for convenience, are hereinafter referred to as register-restoring 105

110

motors; they are not represented in the drawing because they constitute no part of the present invention, and they may be of any desired construction.

5 The ports 2 are those which control the operation of the note-sounding motors, and the four ports *a*, *b*, *c*, *d*, are those which control devices brought into operation by perforations situated preferably near the respectively opposite ends of the tune sheet, for example, devices for effecting:—(a) the stoppage of the music roll without rewinding; (b) the stoppage of the music roll after rewinding; (c) the stoppage of the music roll and rewinding, and (d) the restarting of the music roll after rewinding.

The register control ports 3, 4 are situated in alignment with the ports *a*, *b*, or *c*, *d*, not because the perforations 6, 7 which are 20 adapted to coöperate with such register control ports 3, 4, would have any effect upon the ports 2 did they travel over them, but for the reason that the ports 2 being those which control the note-sounding motors, 25 would necessitate the presence of note perforations at parts of the tune sheet where they would conflict with the register control perforations 6, 7. Hence it is that the register control ports 3, 4 are situated adjacent 30 to ports *a*, *b*, or *c*, *d*, which necessitates the presence of perforations only near the respectively opposite ends of the tune sheet 5, at which parts the presence of the register control perforations 6, 7 is obviously unnecessary.

8 are the ordinary tune sheet note perforations which, when regitsering with the ports 2, cause the actuation of the respective note-sounding motors, and 9 are the partitions between adjacent ports 2, *a*, *b*, *c*, and *d*.

140 Each of the control perforations 6, 7 (these are hereinafter referred to as register control perforations) is of such small size that individually it will have no effect 145 when it registers with any of the tracker board ports *a*, *b*, *c*, *d*, and for convenience these ports *a*, *b*, *c*, *d* and the ports 2 are hereinafter referred to as normal ports. The said perforations are arranged in two 150 parallel rows of series or groups, each series or group with the spaces between the perforations of such group, extending over a linear distance approximately equal to the over-all length of the register control port 155 3 or 4, which latter, on the other hand, are of such length as will enable a sufficiency of the said register control perforations of each individual group to simultaneously register therewith. In the example represented each 160 series or group consists of seven perforations each preferably about one millimeter in diameter and about two millimeters from its neighbor. With the register control perforations 6, 7 of this size and thus spaced 165 apart, it is impossible for any two of them

to simultaneously register with any of the normal ports *a*, *b*, *c*, *d*, and consequently although these perforations may pass over the said normal ports, the instrument, as above described, will not be affected thereby. Moreover, as the distance between a normal port *a*, *b*, *c*, or *d*, and the respective adjacent register control port 3 or 4 is not less than the diameter of a register control perforation, no one of these perforations can simultaneously coöperate with a normal port and a register control port. The register control perforations 6 or 7 of each series or group are however sufficient in their collective area to effect the operation of the respective register restoring motor when, by any lateral deviation of the tune sheet 5 from its normal course, they come into register with the respective register control port 3 or 4 as represented for example in Fig. 2, in which 170 figure some of the register control perforations of both of the rows are shown in register with the respective register control ports 4.

The different series or groups of each 175 row of register control perforations 6 or 7 are in staggered relationship to the different series or groups of the other row, and the space between any two successive groups is approximately equal to the length of each 180 of the groups. By this arrangement the two rows of register control perforations 6, 7 alternate in having their groups alongside of the respective register control ports 3, 4 and there will always be a full complement 185 of the said perforations either alongside of, or in register with, the respective register control port or ports. By this alternation of the respective series of groups of register control perforations 6, 7, a great 190 advantage is obtained over existing arrangements inasmuch as, although the said perforations exercise a continuous control, the tune sheet 5 is not dangerously weakened 195 as would be the case were these register control perforations arranged in one continuous or unbroken line extending throughout the length of the tune sheet as has heretofore been proposed.

When the tune sheet 5 is traveling relatively to the tracker board 1, in the correct position necessary for the note perforations to properly register with the respective normal ports 2, the register control perforations 6 and 7 pass between the respective 120 register control ports 3, 4, without registering with either of them as represented in Fig. 1, consequently the register-restoring motors remain at rest. When, however, the tune sheet is traveling out of correct position relatively to the tracker board 1, say 125 too much toward the right-hand side, and the registration between the note perforations 8 and normal ports 2 is disturbed or in danger of being disturbed, the two rows 130

of register control perforations 6, 7 come into register with the respective register control ports 4, as shown in connection with both sets of perforations 6 and 7 in Fig. 2, and thereby effect the operation of the corresponding register restoring motor which restores the normal relationship between the tune sheet and tracker board. During the brief period that the 10 register control perforations 6, 7 are traveling in register with the register control ports 4 as just mentioned, they also travel in register with the normal ports b, d respectively, but as no two of them can simultaneously register with any one of such 15 normal ports, and the area of each such perforation is, as aforesaid, insufficient to have any effect on the motors connected with the said normal ports, those motors will remain at rest until the tune sheet perforations respectively appertaining to these 20 ports a, b, c, d come into register with them.

I claim:—

1. A tracker board having two functionally different ports arranged in tracking alinement with each other transversely of the tracker board, of relatively different dimensions in that direction and adapted to coöperate with a tune sheet having perforations which uncover both of said transversely-alined ports and are of such dimensions measured longitudinally of the tracker board relatively to the dimensions measured respectively in the same directions of the 35 said ports that these perforations render only one of the said ports responsive.

2. A tracker board having register control ports arranged in tracking alinement transversely of the tracker board with certain 40 ports belonging to the ordinary series of ports in said board and adapted to coöperate with a tune sheet having control perforations which uncover both of said transversely-alined ports and are of such dimensions measured longitudinally and transversely of the tracker board relatively to the dimensions measured respectively in the same directions of the said certain ports that such perforations although uncovering both 45 the register control ports and the other ports will render only the said register control ports responsive.

3. A tracker board having register control ports arranged to the front and rear of certain 50 ports belonging to the ordinary series of ports in said board and in tracking alinement therewith transversely of the said board and adapted to coöperate with a tune sheet having control perforations which uncover both of said transversely-alined ports and are of such dimensions measured longitudinally and transversely of the tracker board relatively to the dimensions measured respectively in the same directions of the 55 said certain ports that such perforations al-

though uncovering both the register control ports and the other ports will render only the said register control ports responsive.

4. A tracker board having register control ports of greater length and lesser width 75 than certain normal ports with which said register control ports are permanently alined transversely of the tracker board and adapted to coöperate with a tune sheet having control perforations which uncover both of said transversely-alined ports and are of such dimensions measured longitudinally and transversely of the tracker board relatively to the dimensions measured respectively in the same directions of the said certain normal ports that such perforations although uncovering both the register control ports and the other ports will render only the said 80 register control ports responsive.

5. A tracker board formed with pairs of 85 register control ports out of line with the series of ordinary ports extending longitudinally of the same tracker board and of greater length transversely and lesser width than those ports and adapted to coöperate 90 with a tune sheet having a line of register control perforations of such a width that said perforations can pass between members of such pairs of ports without overlapping either, and uncover either of those members 95 to render it responsive and also uncover the said ordinary ports without rendering them responsive.

6. A tracker board provided with a series 100 of ordinary ports extending in a row lengthwise of said board, said board being further provided with registry control ports, said registry control ports being each formed in two parts permanently in alinement transversely of the tracker board with and at the 105 front and back respectively of one of said ordinary ports, said control ports extending transversely of said board relatively to said ordinary ports, the dimension of each of said control ports measured in the direction of the travel of the tune sheet being greater 110 than the dimension of each of the ordinary ports measured in the same direction.

7. In an automatic musical instrument, the combination with a tracker board having 115 functionally different ports arranged in alinement one with another in the direction of travel of the tune sheet, of a tune sheet having a succession of small perforations also alined in the direction of travel of the 120 tune sheet, the ports being so proportioned relatively to the perforations and to the distance between immediately following perforations, that when the latter pass over the alined ports, one only of such ports will be 125 operated.

8. In an automatic musical instrument, the combination with a tracker board having register control ports arranged to the front and rear of certain ports belonging to 130

the ordinary series of ports in the said board and in alinement therewith transversely of that board, of a tune sheet having a succession of small perforations alined in the direction of travel of the tune sheet, the ports being so proportioned relatively to the perforations and to the distance between immediately following perforations, that when the latter pass over the alined ports, only the control ports will be operated.

9. In an automatic musical instrument, the combination with a tracker board having register control ports of greater length and lesser width than certain normal ports with which said register control ports are alined in the direction of travel of the tune sheet, of a tune sheet having a succession of small perforations also alined in the direction of travel of the tune sheet, the perforations being of such dimensions measured transversely to the direction of travel of the tune sheet, and the distance between immediately following perforations being such relatively to the corresponding dimensions of the ports, that when the perforations pass over the

alined ports, only the control ports will be operated.

10. In an automatic musical instrument, the combination with a tracker board formed with pairs of register control ports out of line, in the direction transverse to that of the travel of the tune sheet, with the series of ordinary ports extending longitudinally of the tracker board, and of greater length and lesser width than said ordinary ports, of a tune sheet having a succession of small register control perforations alined in the direction of travel of the tune sheet and of such width, that said perforations can pass between members of such pairs of ports without overlapping either, and uncover either of those members to render it responsive and also uncover the said ordinary ports without rendering them responsive.

In witness whereof I have hereunto set my hand in the presence of two witnesses.

JAMES JOHN WALKER.
